(57) **CLAIM**

The ornamental design for a rechargeable personal home-use skin treatment device with charging cradle, as shown and described.

DESCRIPTION

FIG. 1 is a top, front, right side perspective view of a rechargeable personal home-use skin treatment device with charging cradle comprised of a treatment device with cover and a cradle, this figure showing the treatment device with cover on in the cradle;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, front, right side perspective view of the rechargeable personal home-use skin treatment device with charging cradle showing the cradle removed for ease of illustration;

FIG. 9 is a front elevational view thereof;

FIG. 10 is a back elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a top, front, right side perspective view of the rechargeable personal home-use skin treatment device with charging cradle showing the treatment device with cover on, removed for ease of illustration;

FIG. 16 is a front elevational view thereof;

FIG. 17 is a back elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is a top, front, right side perspective view of the rechargeable personal home-use skin treatment device with

(Continued)

charging cradle showing the treatment device with cover off, removed for ease of illustration;
FIG. 23 is a front elevational view thereof;
FIG. 24 is a back elevational view thereof;
FIG. 25 is a left side elevational view thereof;
FIG. 26 is a right side elevational view thereof;
FIG. 27 is a top plan view thereof; and,
FIG. 28 is a bottom plan view thereof.
The broken lines in the drawings illustrate a claim boundary and form no part of the claimed design.
